UNITED STATES PATENT OFFICE.

CHARLES F. MARTINE, OF BOSTON, MASSACHUSETTS, ASSIGNOR OF ONE HALF TO WILLIAM H. KIMBALL, OF SAME PLACE.

LENS ATTACHMENT FOR LAMPS.

SPECIFICATION forming part of Letters Patent No. 293,586, dated February 12, 1884.

Application filed September 6, 1883. (No model.)

To all whom it may concern:

Be it known that I, CHARLES F. MARTINE, a citizen of the United States, residing at Boston, in the county of Suffolk and State of Massachusetts, have invented a new and useful Improvement in Lens Attachments for Lamps, of which the following is a specification.

The object of my invention is to provide a simple and ready means for applying a magnifying-lens to the chimney of an ordinary coal-oil lamp, and also for readily adjusting the lens in relation to the flame of the lamp, so as to change the direction of the magnified rays as desired.

15 The invention consists in a means of connecting the lens to a holder, which is provided with a hook on its upper end for suspending it from the top of a lamp-chimney, so that the lens can be adjusted or moved higher or lower 20 on the chimney and held in position by friction or pressure of the connecting parts.

25 The invention also consists in a peculiar means for connecting the bail or wire to the rim or frame that surrounds the edge of the lens.

Referring to the accompanying drawings, Figure 1 represents my invention as applied to an ordinary coal-oil-lamp chimney. Fig. 2 is a front elevation of a lens with my invention 30 attached. Fig. 3 is a side view of the same. Fig. 4 is a detail view, showing the mode of attaching the bail to the lens-frame.

A represents the chimney of a coal-oil lamp.

B is a concavo-convex lens of any suitable 35 size or degree of convexity.

Surrounding the lens B is a metal rim or frame, C, in one portion of which, on the inner side, are stamped two grooves, d d, at right angles to or transversely with the length of the 40 rim, (this being done before the rim is attached to the lens.) When the rim or frame C is secured to the lens, the ends of a wire loop or

bail, D, are forced into the grooves d d, which latter are then pressed down, so as to firmly hold the loop D and secure it to the lens without the necessity of soldering. 45

E represents an elastic holder, composed of a piece of sheet-tin formed with a hook at its upper end, for hooking over the top of a lamp-chimney, A. The lower end of the holder E 50 is bent round in a circular form, and provided with holes, through which are passed the two sides of the loop D, the said loop passing through two thicknesses of the lower bent end, as indicated in Fig. 3, by which means the loop 55 D can be readily moved up or down and adjusted on the holder E, and in consequence of the friction the loop will be held in any desired position. The friction, if ever relaxed by use, can be readily increased by bending .60 the curved end of the holder E. The resiliency of the holder also aids the friction.

The holder E, instead of being made of sheet metal, may be composed of wire with the lower ends bent to hold the loop D with the proper 65 friction.

What I claim as my invention is—

1. The combination, with a lamp-chimney, A, of a holder, E, having a hook at its upper end, and curved and perforated at its lower 70 end, F, and the sliding loop D, attached to the frame C of a lens, B, substantially as and for the purpose set forth.

2. The rim or frame C of a lens, B, constructed with grooves d d, in combination with 75 the loop D, as and for the purpose set forth.

In testimony whereof I have signed my name to this specification in the presence of two subscribing witnesses.

CHARLES F. MARTINE.
